UNITED STATES PATENT OFFICE

WILLIAM F. ROBERTSON, OF CINCINNATI, OHIO

HINGE

Application filed January 30, 1929. Serial No. 336,062.

This invention relates to improvements in hinges for use on gates and the like. The improvements are particularly in regard to the connection of the respective hinge elements to the fence post and gate, to the adjustability of the gate carrying element relative to the post, and to the automatic gate closing features of the hinge.

It is an object of this invention to provide a gate hinge comprising pintle and eye elements, the engaging surfaces of the elements formed to provide a camming surface whereby the weight of the gate gravitates the eye elements on the pintles and causes the gate to automatically close.

It is another object of this invention to provide a gate hinge in which the eye element is sectional for adjustment and assembly about the gate post and about a headed pintle, and to provide therefore that the assembled eye is incapable of removal from the pintle. The headed pintle prevents easy removal of the gate from the pintles, it being necessary to remove the clamping bolts holding the eye in place about the pintles in order to remove the gate. It has been the custom to turn the pintles in opposite directions to prevent removal but that arrangement put all the weight of the gate on the upper pintle and the lower merely served as a means for maintaining the gate on its hinge axis being inutile as a support. The present invention obviates the necessity of this arrangement and both the pintles serve as supports.

Still another object is to provide an adjustable means for mounting the hinge pintle on the fence post which is adjustable to suit various sizes of posts, and to furthermore provide that the pintle element is adjustable relative to its attaching means, and, therefore, adjustable laterally of the post to adjust the gate relative to the fence posts of the gateway and to insure the proper swing and location of the gate relative to a latch on the opposite side of the gate.

Other objects and further advantages will be more fully set forth in a description of the accompanying drawings, in which:

Figure 1 is a fragmentary side view of the hinge showing it attached to a fence post and supporting a gate.

Figure 2 is an end view of the hinge looking at the same from the gate-attaching side thereof.

Figure 3 is a sectional view taken on line 3—3, Figure 1, showing the sectional construction of the eye element.

Figure 4 is a sectional view taken on line 4—4, Figure 3, illustrating the adjustable mounting of the pintle relative to the fence post.

Referring to the drawings, the pintle of the hinge, indicated at 5, is adjustably supported on an attaching clamp or bracket 6 and the bracket clamped about a fence post 7. An eye element 8 is shown clamped about a side upright 9 of the gate.

The pintle, as best shown in Figure 4, comprises a block portion 10 formed at the lower end of the pintle and a headed stud 11 rising from the block. The block portion 10 is provided with horizontally disposed grooves 12 in its sides for receiving arms 13 of the bracket 6, and is further provided with a rectangular bore 14 extending therethrough at right angles to and between the grooved sides. The end of the block portion 10 adjacent the stud is circular and the shoulder 15 between this portion and the stud 11 is provided with a pair of V-shaped notches 16 diametrically opposite relative to the stud.

The eye element 8 mounted on the pintle comprises half sections 17 clamped about the gate upright by means of clamping bolts 18, and the respective half sections have corresponding extensions 19 adapted to encircle the pintle 5. These extensions make up a split eye bore and are adapted to be fitted snugly about the pintle by manipulating the clamping bolts 18 and shifting the sections on

the gate upright. The adjacent faces of the sections of the eye are provided with a tongue and groove connection 17^a for interlocking the sections against relative vertical movement.

- 5 A pair of lugs 20 is formed on the under-side of the eye element, one on each section, and are co-related with the V-shaped notches on the pintle so that these lugs and grooves 10 are interengaged when the gate is closed. Opening of the gate causes the eye element to rise relative to the pintle, the lugs 20 camming out of the notches 16 to some position on the inclined faces of the groove, from 15 which position the weight of the gate acts to gravitate the eye element into interfitted position in the grooves when the gate is released.

A head 5^a is provided on the pintle and a sufficient clearance is allowed between the 20 eye and the head to permit the rising of the eye in the grooves. The head 5^a prevents removal of the gate from the pintles without disassembly of the eye element.

The clamping bracket or strap 6 for attaching the pintle to the fence post, comprises, a half section 21 and quarter sections 22. The quarter sections 22 have the arms 13 extending parallel with the line of the closed gate and spaced apart to straddle the 30 block of the pintle and engage in the respective grooves 12 thereof. The other arms 24 of the quarter sections extend out in relation to the arms 25 of the half section 21 after the manner of the conventional clamping bracket, 35 and the whole arrangement is clamped about the fence post by means of bolts 26. The arms of the clamping bracket disposed at each side of the pintle block are provided with horizontally disposed slots 27, these slots 40 traversed by a bolt 28 for attaching the arms to the block, the bolt traversing the rectangular bore 14 in the pintle block.

The rectangular bore in the pintle block is of greater width than the diameter of the bolt 45 so that the pintle is adjustable relative to the arms of the bracket, not only the difference in length of the slot over the diameter of the bolt, but in addition, is adjustable the difference in the width of the square bore over the diameter of the bolt. This enables a considerable lateral shifting of the pintle on the 50 clamping bracket so that the gate may be properly set between the posts and subsequently adjusted when the posts sag and the 55 gate is unproperly situated relative to the latch thereof.

Having described my invention, I claim:

1. A hinge, comprising, in combination with a fence post and a gate, a pintle element, 60 an eye element, said elements securing the gate to the post, one element having a shoulder formed thereon having diametrically oppositely disposed V-shaped notches and the other element having lugs engaging said 65 notches on the first, an integral head formed

on said pintle, the pintle being of sufficient length to permit movement of the eye between the head and shoulder of the pintle as one element shifts vertically on the inclined surface of the other and said eye formed of split construction permitting assembly laterally about the pintle. 70

2. In a hinge construction, a pintle, means for mounting said pintle, an eye engaging said pintle, said eye comprising half sections, 75 each of said half sections providing a portion for encircling the element to which the eye is attached, and clamp bolts traversing said sections at each side of the support for securing the eye sections rigidly about said element and adjusting the eye about the pintle, said sections, when disposed about said element to which the eye is attached, being sufficiently spaced apart to provide for relative 80 rotative movement about the element to 85 which the eye is attached.

3. A gate hinge, comprising, a pintle, a bracket for mounting said pintle, an eye mounted on said pintle, said bracket having means for clamping the same to a post and laterally extending arms disposed at respectively opposite sides of the pintle, said arms longitudinally slotted, said pintle provided with a bore, and a bolt extending through the bore and having clearance therein and 95 extending through the slots, whereby the pintle may be clamped between the arms and adjusted laterally of the post. 90

4. A hinge, comprising, a pintle, an eye mounted on said pintle, a bracket for said 100 pintle, means for attaching said bracket to a support, said bracket having parallel arms extending therefrom and straddling said pintle, said arms slotted longitudinally, and a bolt traversing said pintle and slots to adjustably 105 clamp the pintle between said arms.

5. A hinge, comprising, a pintle, an eye about said pintle, a bracket for mounting said pintle, said bracket having laterally extending parallel arms straddling said pintle, said 110 pintle grooved at respectively opposite sides to receive said arms, said arms slotted longitudinally, and a bolt traversing said pintle and slots to adjustably clamp the pintle between said arms. 115

6. A hinge, comprising, a pintle, an eye mounted on said pintle, a bracket for said 120 pintle, said bracket adapted to encircle a support and having laterally extending parallel arms straddling said pintle, said pintle grooved at respectively opposite sides to receive said arms and having a bore extending transversely between said grooved sides, said arms slotted longitudinally, and a bolt traversing the bore of said pintle and said slots to adjustably clamp the pintle between said arms, said bore in the pintle being of greater width than the diameter of said bolt. 125

7. A hinge, comprising, a headed pintle, means for mounting said pintle, an eye engag- 130

ing said pintle, said eye comprising half sections, an element supported by said eye, the sections of said eye joined about said supported element and said pintle, a tongue and 5 groove connection formed on the adjoining faces of the sections, and clamp bolts traversing said sections, one at each side of the element to be supported.

In witness whereof, I hereunto subscribe
10 my name.

WILLIAM F. ROBERTSON.
